UNITED STATES PATENT OFFICE.

EMIL CLAVIEZ, OF CHEMNITZ, GERMANY.

DOUBLE-PLUSH FABRIC.

SPECIFICATION forming part of Letters Patent No. 611,104, dated September 20, 1898.

Application filed May 14, 1895. Serial No. 549,303. (Specimens.) Patented in Austria January 22, 1894, No. 44/1,052; in France January 31, 1894, No. 235,945; in England February 16, 1894, No. 3,374, and in Italy March 31, 1894, No. 36,100.

To all whom it may concern:

Be it known that I, EMIL CLAVIEZ, a subject of the King of Saxony, and a resident of Chemnitz, in the Kingdom of Saxony and Empire of Germany, have invented certain new and useful Improvements in Double-Plush Fabrics, of which the following is a specification.

My invention is embodied in patents of the following countries: Austria, No. 44/1,052, dated January 22, 1894; France, No. 235,945, dated January 31, 1894; Great Britain, No. 3,374, dated February 16, 1894, and Italy, No. 36,100, dated March 31, 1894.

In the process of manufacturing woven pile fabric or multicolored jacquard double plush it has heretofore not been possible to produce even designs, such as are required for the production of carriage-robés, curtains, quilts, &c.

According to the present invention a woven pile fabric or multicolored jacquard double plush—that is to say, two tissues, one above the other—can be produced which are exactly alike with respect to the design or image of the plush. The colored threads necessary for the production of the design of the plush are, however, not hidden in one ground fabric at the places at which they do not form plush, but they are divided from the two ground fabrics, being superposed one above the other and being now produced simultaneously. If, for instance, a color being otherwise covered in the upper ground fabric should suddenly appear in the plush, the corresponding plush-thread passes from the upper fabric to the lower fabric and is bound in by a special shuttle-throw or the so-called "stitching-weft." Should, further, a color appear in the plush which has been covered in the lower fabric, the respective plush-thread passes from below upward and is there also bound in by a special shuttle-throw or the so-called "stitching-weft." After carrying in a stitching-weft a second throw of the ground-shuttle is executed either for the one or the other fabric, being designed to give to the whole fabric a more solid ground and a better hold. For the manufacture of such a tissue shafts and harnesses are necessary. The

shafts are used to make the two ground fabrics, one above the other, while the harnesses or the harness parts effect the binding of the plush-threads in the faces of the upper and the lower fabrics, respectively. These shafts 55 and the harnesses are divided into two parts—one forming plush for the upper fabric and the other forming plush for the lower fabric—and operate in such a manner that the threads of the plush and of the ground never cross during 60 the weaving and are so arranged that they go back to their normal position after every stroke of the shuttle. The shuttle is thrown twice, once in each fabric, and thereby a double fabric is produced, which after the 65 cutting of the plush furnishes two single fabrics having everywhere even and pure plush.

In order that my invention may be fully understood, I will proceed to describe it with 70 reference to the accompanying drawings, in which—

Figure 1 is a longitudinal section showing a portion of my double fabric in course of construction and the normal position of the 75 shafts and the harness parts of the loom, in which the plush-threads run parallel and cover each other reciprocally in the upper and lower fabric. Fig. 2 is a longitudinal section showing one part of the double fabric 80 where the plush-threads of the lower fabric are bound into the upper fabric, the ground-threads of both fabrics not being represented. Fig. 3 is a longitudinal section of that part of the double fabric where the plush-threads of 85 the upper fabric are bound into the lower fabric. Fig. 4 shows the grounds alone in longitudinal section. Fig. 5 shows the whole double fabric in longitudinal section, the plush-threads being shown bodily covering each 90 other in the upper fabric and binding downwardly with the plush-threads of the lower fabric, which bind upwardly. Fig. 6 is a detail plan view of the top of the double fabric. Fig. 7 is a detail transverse section thereof on the 95 line 7 7, Fig. 6. Fig. 8 is a detail horizontal section on the line 8 8, Fig. 5, showing a top plan view of the lower piece of the divided fabric. Fig. 9 shows the position of the shafts and harness parts and the double fabric when 100

the upper ground-weft has been thrown in. Fig. 10 shows the position of the shafts and harness parts when the lower ground-weft has been thrown in. Fig. 11 shows the position of the shafts and harness parts when the upper quilting-weft is thrown in. Fig. 12 shows the position of the shafts and harness parts when the lower quilting-weft is thrown in. Fig. 13 shows the position of the shafts and harness parts when the next upper ground-weft is thrown in. Fig. 14 is a tabular statement setting forth the positions of the shafts and harness parts at each stroke of half-periods.

15 1 are the ground-threads of the upper fabric, and 2 are the ground-threads of the lower fabric, forming the foundation of my improved double plush.

20 3 are the pile-threads of the upper fabric, and 4 are the pile-threads of the lower fabric.

25 5 and 6 are parts of the harness that move the pile-threads 4 of the lower fabric, and 7 and 8 are parts of the harness that move the pile-threads 3 of the upper fabric.

30 11 and 12 are the shafts for the ground-thread 1 of the upper fabric, and 9 and 10 are the shafts for the ground-threads 2 of the lower fabric.

35 s' s^3 are the stitching-wefts, binding fast the plush-threads above, and g' g^3 represent the ground-wefts in the upper fabric.

40 s^2 s^4 are those stitching-wefts which bind the plush into the lower goods.

45 G^2 G^4 represent the ground-wefts of the lower fabric.

The different designations of the shafts and harnesses should not mislead, as they are solely designed to serve to the diagrammatical illustration of the tissue.

50 In Figs. 1, 9, 10, 11, 12, and 13 it is shown how the colored plush-threads, being represented by lines of different character, are divided upon two groups of harness 5 6 7 8 in a common jacquard machine in such way

55 that one group of harness receives one part of the colored plush-threads and the other group of the harness receives the other part of the same. Thus in Fig. 9 the group of harness 7 and 8 carries the plush-threads 3

59 of the upper fabric and the group of harness 5 and 6 carries the plush-threads 4 of the lower fabric. Each group must therefore be divided in as many parts as it is required to carry threads. In the accompanying figures

64 four colors of plush-threads are shown as an example, so that one part is divided into the parts 5 and 6 and into the parts 7 and 8. The ground-binding of the upper and lower fabric is shown separate from each other and

69 is indicated in the drawings by lines made of dashes. The shafts for the ground-binding of the lower fabric are designated here with the numerals 9 and 10, the shafts of the upper ground fabric with 11 and 12.

75 The wefts serving for the fastening of the plush-chain parts, and which are called here "stitching-wefts," for the sake of simplicity

are marked with the letter s , and the ground-wefts are marked with the letter g . Moreover, the shafts are shown, for greater clearness, a little farther apart than in practice, so that the warp-eyes of the several groups of shafts 9 10 11 12, being otherwise in one plane, are shown in the present case somewhat apart. The same must be said of the groups of harness 5 6 7 8.

70 The process of manufacturing this fabric can be explained in the following manner: When the shafts and the harness parts in Fig. 9 are in such a position that the ground-weft g' can be thrown in, all plush-chain threads 3 of the upper fabric, and also the harness parts 7 and 8, as well as the shaft 11, must be lowered, so that in the middle plane of the plush-tissue the corresponding shed is 85 formed for the weft g' to be thrown into the upper fabric.

75 In Fig. 9 the position is shown in which the ground-weft g' has been thrown in. When this is effected, the batten moves the ground-weft g' in the direction of the arrow and is beaten against the fabric. At the same time the parts of harness 7 and 8 and the shafts return into their normal position. When this is effected and while the batten returns, the parts of harness 5 and 6 and the shafts 9 are 90 lifted and the ground-weft g^4 is thrown into the lower fabric in the position shown in Fig. 10. The same is beaten by the batten in the direction of the arrow, and the harness parts 95 5 and 6 and shaft 9 are brought back into their normal position. Herefrom results that the two ground-wefts are thrown in one after the other. After this the next stitching-weft must be thrown into the upper fabric, and 100 from the lower fabric these plush-threads are lifted, which should appear in the plush. Suppose at this point the color should appear in the plush part represented by the line dash-dot-dot-dash and in this part the harness part 6 is lifted and the shaft is lowered, Fig. 11, so that again in the middle plane of the fabric a shed is formed and the stitching-weft s^3 , designed for the upper fabric, can be thrown in. The same is beaten in by the 105 batten in the direction of the arrow and the part of harness and shaft return into their normal position. When this is done, the second stitching-weft is thus thrown into the lower fabric, and to this end from the upper 110 fabric that row of plush-chain threads is lowered which should appear in the plush. Suppose a color should appear in the plush represented by the line dash-dot. In this case the shaft 9 is lifted, Fig. 12, the harness part 7 is lowered, the stitching-weft s^4 is 115 thrown in, and shafts and harness brought to their normal position. It is self-evident that during this procedure the thread of plush chain represented by the line dash-dot-dot-dash is also bound in, for the reason that it 120 belongs to the lower fabric and that it serves for the completion of the design resulting from the plush-chain parts at the left being

125 130 135

bound in upwardly. When now both quilting-wefts are thrown in, the play shown in Fig. 9 is repeated—*i. e.*, all plush-chain threads of the upper fabric are lowered and a new ground-weft g^3 is thrown in. To this end the harness parts 7 and 8 and shaft 12 must be lowered so that Fig. 13 corresponds to the starting, Fig. 9. Thus it can be seen that in fact the plush-chain threads do not cross but run parallel to each other during the work. The plush thus obtained is cut between the fabrics, and the separated fabric parts are rolled upon beams. This new process of manufacture is also characterized by the introduction of a ground-weft after the lifting and lowering of the harness parts. The batten having beaten home the wefts, the shafts and harness parts go back to their normal position and the batten beats a second time, so that both goods remain completely separate from each other.

The complete binding of the fabric represented in Fig. 5 is effected in eight periods. In the first half the shafts and harness parts take the position for the introduction of the respective weft, and in the second half they go back to their normal position. At the end of each half-period the batten strikes.

The shaft or harness parts to be lifted or lowered and the ground-wefts to be introduced each time can easily be seen from the accompanying table, (shown in Fig. 14.) It should be observed, besides, that in the first

and fifth period, during which the wefts are introduced for the upper fabric, the whole harness 5 6 is down and that in the second and sixth period, during which the wefts for the lower fabric are introduced, the whole harness 7 8 is up, while in the remaining periods only the cords of the harness are lifted 40 and lowered, the chain threads of which are intended to form velvet in both goods, according to the pattern.

Having thus described my invention, the following is what I claim as new therein and 45 desire to secure by Letters Patent:

The double-plush-fabric blank comprising upper and lower grounds each composed of ground-warps and ground and stitching wefts, series of upper and lower pile warp-threads 50 extending approximately parallel to each other from the upper ground to and from the lower ground and vice versa, and the stitching-wefts alternating with the ground-wefts in each ground and securing the pile-threads 55 to the faces of the grounds; the ground-wefts and stitching-wefts of the upper fabric alternating in position with the ground-wefts and stitching-wefts respectively of the lower fabric and vice versa; substantially as described. 60

In witness whereof I have hereunto set my hand in presence of two witnesses.

EMIL CLAVIEZ.
